UNITED STATES PATENT OFFICE.

CHARLES H. BELL, OF CLEVELAND, OHIO.

WINDOW-SHADE-TRIMMING DEVICE.

SPECIFICATION forming part of Letters Patent No. 717,800, dated January 6, 1903.

Application filed April 10, 1902. Serial No. 102,189. (No model.)

To all whom it may concern:

Be it known that I, CHARLES H. BELL, a citizen of the United States, residing at Cleveland, in the county of Cuyahoga and State of Ohio, have invented certain new and useful Improvements in Window-Shade-Trimming Devices; and I do declare that the following is a full, clear, and exact description of the invention, which will enable others skilled in the art to which it appertains to make and use the same.

My invention relates to window-shade trimmers; and the object of the invention is to provide a trimmer or trimming device where-
15 by a window-shade which has been cut to a given length and wound upon a roller can be shortened as much as may be required to fit a given window or by which a shade can be shortened to the width desired by cutting it
20 directly upon the roller, after which the roller itself can be sawed off and the end bearing replaced thereon, and all this can be done on the spot after getting the measurements of a window, or the device can be used in a furn-
25 nishing department where shades are kept in stock, all substantially as shown and de-
scribed, and particularly pointed out in the claims.

In the accompanying drawings, Figure 1 is
30 a perspective elevation of my improved trim-
mer or trimming device and an end section of
a window-shade and roller and with the de-
vice in trimming or cutting position, as here-
inafter more fully described. Fig. 2 is a plain
35 side elevation of the device itself.

As thus shown, the device comprises two handled members A and B, resembling the handles or corresponding members of what are commonly known as "pliers," and said
40 parts are suitably pivoted together and held by a pivot-screw 2 or its equivalent, as in a pair of shears. The handle portions of these members are preferably of the shape here shown, because of their convenience; but
45 they might be differently shaped and not depart from the invention. They might also be constructed at their extremities to serve for pulling tacks and as screw-drivers, while their "jaws" 3 and 4, so called, are constructed es-
50 pecially for present use. Both the said jaws have substantially the same configuration or outline in both side and plan, and the said

members are preferably made or cast complete in one piece, including jaws and handles. Both jaws are substantially V shape in 55 side elevation. This principle of construction is also maintained in the further means connected with the jaws, and to this end the upper jaw is provided with two blades or cutters 5, which together may be regarded as constituting a single substantially V-shaped cutter or cutting edge; but two sections are used, because it is more convenient to make and to sharpen in this form; otherwise it might be in one piece. The said sections, likewise, are 65 adjustable by means of slots therein and screws 6, which fasten them, so that as the edges become worn away the blade can be adjusted accordingly. The other jaw is provided with a substantially V-shaped trough 70 or extended bearing 7, fixed to the jaw 4 and of such length as to form a steady support for the shade as the cutting progresses. Then having first rolled shade C tightly upon roller D and evenly at both edges the shade can 75 be placed into the trimmer or the trimmer upon the shade, substantially as seen in Fig. 1, and as the shade is rotated with one hand and the trimmer is held with the other the work of trimming is speedily accomplished 80 and the shade is provided with a new clean straight edge, as originally. The roller is then cut off to a corresponding length and its bearing replaced thereon, and then the shade is ready to be put up. 85

One advantage of having bearing 7 of V shape corresponding to the cutter is that it always forms a uniform bearing in respect to the cutter regardless of the size or thickness of the shade, and in this it differs materially 90 from a circular bearing in which the shade might rock. Then by having the blades set as here shown or at some such inclination or angle I obtain a shearing cut, and the resistance at one of the inclined edges is met by 95 the sharp edge of the other, and thus the cutting proceeds at two points with two corresponding bearing contacts on the shade. I have, however, shown this construction as the preferable style or form thereof and might 100 change the shape of both the jaws and the parts 5 and 7 thereon without really departing from my invention.

It will be noticed especially as an impor-

tant feature of this invention that the bearing or trough 7 has such length as to project some distance in both directions from the sides of the cutter-blade. This is necessary in order that the shade shall have a length of bearing for rotation which will hold it steadily in the same relation to the cutter until the trimming is completed; otherwise if there were no such sustaining-bearing there would be a tendency for the shade to rock more or less while in the operation of trimming, and this would produce an uneven edge, which has to be carefully guarded against.

What I claim is—

1. A trimming device for shades having a set of handled jaws pivotally connected, and a substantially trough-shaped support for the shade on one jaw and a cutting-blade to trim the shade on the other jaw, said support for the shade extending in opposite directions from the sides of the cutter-blade, substantially as described.

2. In shade-trimmers, a hand trimming device having a substantially V-shaped trough serving as a support for the shade, and a substantially V-shaped blade to trim the shade arranged to cut substantially midway the length of said trough, whereby the shade is

supported on both sides of the blade when cutting occurs and is held from rocking, substantially as described.

3. In shade-trimmers, a trimming device having handles and a set of jaws, a length-wise support for the shade on one of said jaws and a substantially V-shaped trimming-blade on the opposite jaw arranged centrally between the ends of said support for the shade and whereby firm bearing-points for the rotation of the shade are obtained at each side of said blade, substantially as described.

4. The trimming device for shades substantially as described, having a set of handled jaws, a support for the shade on one jaw and a trimming-blade on the other jaw comprising a pair of blade-sections adjustably mounted in relation to each other and having the cutting edges of said sections of the blade at an angle to each other, substantially as described.

Witness my hand to the foregoing specification this 31st day of March, 1902.

CHARLES H. BELL.
